UNITED STATES PATENT OFFICE

153,930

DESIGN FOR A COMBINED BILLFOLD, KEY CASE, AND COIN PURSE

Charles A. Fox, New York, N. Y.

Application November 6, 1947, Serial No. 142,352

Term of patent 14 years

(Cl. D87—3)

To all whom it may concern:

Be it known, that I, Charles A. Fox, a citizen of the United States of America, residing at New York, in the county of New York and State of New York, have invented a new, original, and ornamental Design for a Combined Billfold, Key Case, and Coin Purse, of which the following is a specification, reference being made to the accompanying drawing, forming a part thereof, in which

Fig. 1 is a perspective view of the key case side of a combined billfold, key case and coin purse embodying my new design;

Fig. 2 is a view similar to Fig. 1 with the key holder element in an open position;

Fig. 3 is an elevational view of the coin purse side of the combined billfold, key case and coin purse shown in Fig. 1; and

Fig. 4 is a bottom edge view of the article as shown in Fig. 1.

I claim:

The ornamental design for a combined billfold, key case, and coin purse, as shown.

CHARLES A. FOX.
